FURNITURE

Cecil W. Farrar, Buffalo, N. Y.

Application September 20, 1932, Serial No. 633,937

Renewed June 5, 1934

18 Claims. (Cl. 45—38)

My invention relates to new and useful improvements in furniture, and more particularly to a structure in which a lavatory basin and a dressing table or the like are combined.

5 An object of my invention is to provide means for supporting the basin.

Another object is to eliminate water and dirt collecting crevices.

Another object is to provide a basin of novel 10 construction.

The invention consists in the improved construction and combination of parts and their ag- 15 groupment in cooperable relation, to be more fully described hereinafter, and the novelty of which will be particularly pointed out and distinctly claimed.

In the accompanying drawings, to be taken as a part of this specification, I have fully and clearly illustrated a preferred embodiment of my in- 20 vention, in which drawings—

Fig. 1 is a view in front elevation of a furniture structure embodying my invention.

Fig. 2 is a top plan view thereof;

Fig. 3 is a view in section on the line 3—3 of

25 Fig. 1;

Fig. 4 is a view in section on the line 4—4 of Fig. 2;

Fig. 5 is a view in section on the line 5—5 of Fig. 4;

30 Fig. 6 is an enlarged detail view in section on the line 6—6 of Fig. 1, and

Fig. 7 is a view in section on the line 7—7 of Fig. 1.

Referring to the drawings by characters of reference, 1 designates a mirror which is carried by laterally spaced supporting members 2, 3 which also support a lavatory basin 4 positioned therebetween and beneath the mirror 1.

The supporting members are preferably alike, 40 and therefore a description of one will suffice for both, the primes of reference characters applied to member 2 designating like parts in member 3. The members 2, 3 are preferably of sheet metal, and each comprises a main cabinet

45 5 and a supplemental cabinet 6 carried by the main cabinet. The cabinet 5 has outer and inner side walls 7, 8 and a top wall 9 which are preferably formed from a single blank of sheet material bent to inverted U-shape form. The

50 side walls terminate at their lower edges in inward directed opposed flanges 10, 11, to which are secured outer and inner bottom side wall or base portions 12, 13 which are stepped inward and downward and terminate in inward directed flanges

55 14 adapted to rest upon a floor or other support

ing surface. The rear vertical edges of the side walls terminate in inward directed opposed flanges 15, 16, respectively, the corner between flange 16 and wall 8 receiving a vertical channel member 17 having its web secured to the flange 16 and one of its forward directed flanges lying against and secured to the wall 8. The channel member extends upward through an aperture in the top walls of cabinets 5 and 6 and terminates some distance above the top wall to provide a support, see Fig. 4. The front vertical edges of the side walls have inward and forward stepped portions 18 providing front wall portions which terminate in rearward directed parallel flanges 19 defining the side edges or faces of a drawer 15 and a door opening for the main cabinet. Within the cabinet and extending from front to rear thereof, there is a liner of sheet metal having side walls 20 aligned with and joining the flanges 19 and having a top wall 21 abutting the top wall 9, the bottom edges of the walls 20 being secured to the base portions 12, 13, as at 22. The cabinet is reinforced by vertically spaced substantially horizontal spacer members 23 positioned between the side walls of the liner and the side walls of the cabinet. The members 23 are preferably in the form of channels having their flanges directed upward, one flange of each member being secured, as at 24, directly to the wall 7 or 8 and the other flange being secured 30 by longitudinal clamping strips 25 to the adjacent liner wall 20. The cabinet has a bottom wall 26, having depending side flanges 27 which are secured to the liner walls 20. At its front edge the wall 26 is turned downward and then 35 rearward, as at 28, to join with a base portion 29, which is stepped downward and rearward in conformity with the base portions 12, 13, to which it is joined at its side edges. The main cabinet is divided internally by a partition 30 into an 40 upper drawer compartment and a lower shelf compartment. A door or closure member 31 carried by hinges 32 secured to one of the flanges 19 serves to close the front of the shelf compartment which contains one or more shelves 33. The 45 rear vertical edges of the liner side walls 20 are turned outwardly, as at 34, substantially in the plane of the rear flanges 15, 16. The back or rear of the cabinet 5 is closed by a wall or plate member 35 which is secured to outturned liner 50 portions 34, and is also secured at its vertical side edges to the flange 15 and the channel member 17, respectively, see Fig. 5. The plate member 35 extends above the cabinet top wall 9 and serves 55 as the rear wall for the supplemental cabinet 6.

being joined at its top edge to a flange 36 depending from the top wall 37 of cabinet 6, and at its side edges to the side walls 38 of the cabinet 6. The side walls 38 have inturned flanges 39 at their bottom edges which rest upon and are secured to the top wall 9. Within the cabinet 6 there is a supporting member 40 secured to the top wall 9 and having upstanding longitudinal flanges 41 which are turned outwardly 10 into engagement with the side walls 38 to which they are secured. The flanges 41 carry longitudinally extending horizontal drawer guides or rails 42 which are vertically adjustable, see Fig. 7, and which are rigidly secured in position by screws 43. A drawer 44 is positioned within the cabinet 6 and has side guiding members 45 which engage and hook over the top and bottom edges of the rails 42 to slidably support the drawer. The drawer compartment in cabinet 5 has horizontal guides or rails 46 which are vertically adjustable and which are held against movement by screws 47 passed through the liner side walls 20 and screw-threaded into backing strips. Within the compartment is a drawer 48 having rigid therewith side guiding members 49 extending longitudinally of the drawer and which ride on the rails 46, preferably being bent or hooked over the top and bottom edges thereof. Each of the drawers may be provided with a pivoted locking dog 49^a cooperable with a notch 49^b in the top face of the guide rail to normally prevent the drawer from being accidentally withdrawn entirely from its cabinet.

The mirror 1 has a surrounding frame 50 which receives the mirror glass 51 which is secured in place by a backing plate 52. The frame 50 is rigidly secured to the channel members 17 by supporting plates 53 which overlap and are fixed to the frame and the members 17 by screws 54. The frame 50 extends between and substantially engages the inner side walls of the cabinets 5, 5', the lower mirror frame member 55 having its lower edge in a plane slightly below the plane of the top walls 9, 9', see Figs. 3 and 4.

The main cabinets are rigidly jointed together at their bottom portions by a horizontally extending iron angle bar 56 having end flanges 57 abutting the base portions 13, 13' to which the flanges are secured by bolts 58 or the like. The main cabinets are also rigidly jointed together at their upper portions by a supporting means, preferably in the form of a substantially horizontal framework which is substantially rectangular in plan view. The framework includes side frame members 59, preferably iron angle bars secured to the walls 8, 8' and extend forwardly from the rear edge of the cabinets, each having a wide top flange 60 and a depending flange 61. The flanges 61 are secured to the cabinet walls 8, 8' by bolts 62 which are threaded into reinforcing plates 63 secured to the inside faces of the walls 8, 8'. The flanges 60 are rigidly joined at their front ends by a downward facing channel iron or bar member 64, and at their rear ends by an iron angle bar 65 having a depending flange substantially in the plane of the cabinet rear walls.

This framework supports the basin 4 which is preferably of cast ceramic material having a top wall 67 through which an integral depending bowl 68 opens. The basin has a front apron or wall 69, side walls 70, and a rear wall 71 which join the top wall along their top edges and each other at their vertical end or side edges to provide a substantially rectangular basin. The

basin also has bottom wall portions 72 which overlie the horizontal flanges 60 and which are joined to the apron and to the side and rear walls. The bottom wall portions are each provided with front and rear elongated apertures or slots 73 which align with apertures 75 through the flanges 60. Adjustably screw-threaded through the apertures 75 there are supporting sleeve members 76 having top recesses 77 in which are positioned annular cushion blocks 78 of rubber or the like on which the bottom wall portions seat. The basin is clamped rigidly to the supporting framework by bolts and nuts 79 extending through the basin bottom wall and the sleeve member 76, the bolts preferably having cross-bar heads to pass through the slots 73, the heads being turned to lie across the slots after insertion. The space between each of the cabinet side walls 8, 8' and the adjacent side edge of the basin top wall and apron is closed and sealed by a strip member 80. Each of the members 80 has a horizontal top portion, a vertical front portion and a short rearward extending bottom portion, and is preferably in the form of a hollow metal moulding, substantially quarter round metal, having an undeturned lip or edge 81 and a vertical flange 82, see Fig. 4. The undeturned edge 81 engages the top basin wall and the apron and lies under the front portion of the basin bottom wall. The vertical flange 82 lies against the cabinet side wall and is fixed throughout its length to the edges of a plate member 83 which extends substantially from front to rear and from top to bottom of the basin. The moulding 80 terminates rearwardly at and in abutting relation to the mirror frame which overlies the rear edge portion of the basin top wall. The plate member 83 has, at its rear vertical edge, a lateral flange 84 which engages the basin rear wall and by its resilience tends to pull the plate member 83 rearwardly so that the vertical portion of the undeturned edge 81 is held tightly against the side edge of the front apron. The bottom edge of the plate member 83 is also provided with a lateral flange 85 which engages the underface of the basin bottom wall and which by its resilience acts to pull the plate member 83 downward and the horizontal top portion of the undeturned edge 81 tightly against the side edge of the basin top wall. The flange 85 terminates at its front end, as at 86, substantially at the rear end of the rearward extending bottom portion of the moulding 80, see Fig. 3. The vertical flange 82 is urged into tight engagement with the cabinet side wall by resilient means 87, preferably a pad or slab of sponge rubber or the like which lies between the basin side wall and the plate member 83. The joint between the basin and the cabinet side walls is thus closed and sealed by means permitting relative movement between the parts which may occur from expansion and contraction or from other causes. The moulding 80 also accommodates for and conceals slight irregularities in the size of the basin casting.

The basin 4 has on its top wall 67 and preferably substantially centrally of the rear edge of the bowl 68, a protuberance 88, preferably cast integral with the basin and having a portion or lip 89 which overhangs the rear edge of the bowl. The protuberance 88 comprises an inlet conduit member and extends rearward of the rear wall 89' of the bowl. Through the protuberance 88 there is a conduit or passageway 90 which at its inlet end opens downward through the basin top

wall in back of the bowl rear wall and which at its outlet end opens downward and forward into the bowl. The inlet end of conduit 90 receives a pipe 91 which is sealed in the bore of the conduit by a compressed rubber sleeve 92 or the like, and which is threaded at its other end into a T-fitting 93. The arms of the fitting 93 are connected by branch conduits to hot and cold water control valves 94, of which but one is shown, having supply pipes 95. The bowl has a drain or discharge outlet passage 96 in its bottom wall which is connected to a discharge or drain pipe 97. The outlet 96 has a valve 98, preferably of the pop-up type controlled by a cam 99 on a shaft 100 journaled through the wall of the pipe 97. The bowl rear wall 89' has an overflow passageway 101 therein which opens at its inlet end, as at 102, through the top portion of the front face of the wall 89' into the bowl beneath the overhanging lip 89. The other end of the overflow passageway 101 discharges into the outlet passage 96 beneath the valve 98 so as to bypass the excess water around the valve and to prevent the water level rising in the bowl above the overflow opening 102. The control valves 94 are operable by hand-grips or handles 103 carried by the apron 69 and projecting from the front face thereof. The handles 103 are fixed to shafts 104 journaled in apertures through the apron 30 and extend rearward beneath the basin top wall where they are joined rigidly with the stems of valves 94. The valve 98 is preferably controlled by a pull wire 105 connected at one end to a lever arm on a valve operating cam shaft 100 and at its other end connected to a lever arm 106 in rear of the apron. The arm 106 is fixed on a shaft 106' which is journaled through an aperture in the apron and which is provided in front of the apron with an operating handle 107. This mechanism for controlling the valves 94 and 98 forms part of my copending application, Serial No. 602,413, filed April 1, 1932, so that more detailed description thereof is not necessary herein.

The drain pipe 97 is concealed by a panel member 108 which extends between the cabinet side walls 8, 8' and has rearward extending side, top and bottom flanges 109. The member 108 fits within a substantially U-shaped frame having side frame members 110 joined by a bottom frame member 111. The frame members 110 and 111 have at their inner marginal edge a continuous rearward offset portion or flange 111' providing a seat for the rear edge of the flange 109. The frame members 110 are rigidly secured to the side walls 8, 8'. The member 111 seats on a base portion 112 to which it is secured by clips 112' or the like, the portion 112 being stepped downward and rearward in conformity with the portions 13, 13'. The ends of the portion 112 are provided with rearward extending flanges 113 which are secured to the portions 13, 13' by bolts or the like 114. The lower edge portion of the panel member 108 is provided on its rear face with clips 115 which engage over the top edge of the frame member 111 to hold the bottom edge of the panel member in position. The panel member is held at its top which lies closely adjacent the underside of the basin by screws 116 or the like threaded into the flanges 111' of the vertical side frame members 110. Another panel member 117 is provided which conceals the basin supporting means and the underside of the basin. The member 117 has upward extending side flanges 118 which abut the cabinet

side walls and has a depending flange 119 at its rear edge which extends downward behind the panel member 108 and engages the rear faces of the flanges 111' so as to close the horizontal space between the panel members. A screw or the like 120 is preferably provided for securing the members 108 and 117 together, the screw being threaded into the flange 119 so that the flange is pulled tightly against the frame members. The member 117 is inclined slightly in a forward and upward direction and at its front edge has an upturned flange 121 which lies against the front flange of the channel member 64 to which it is secured by one or more screws 122 or the like. The top edge of the flange 121 has a rearward extending lip 123 which extends between the basin and the channel member and which preferably engages the top face of the channel member 64.

The structure is preferably wired for electricity and has a conduit outlet or junction box 124 mounted on the rear angle-iron 56. From the box 124 sheathed or armored wiring 125 leads to outlet sockets 126 preferably supported in the side walls of the supplemental cabinets 6, 6', see Fig. 4.

The elements comprising or making up the mirror, the supporting members or cabinets and the basin supporting means, respectively, are preferably joined together by spot welding or the like, except as is otherwise specified for the joints between particular elements or parts.

The structure is assembled as follows: The main cabinets 5, 5' carrying the supplemental cabinets 6, 6' are connected rigidly together by the basin supporting framework and by the base member 112 and angle-iron 56. The basin 4 has the strip members 80 applied thereto and is then positioned between the cabinet walls 8, 8' and upon the supporting framework with the basin bottom wall portions 72 resting upon the resilient cushioning member 78. If necessary, the sleeve members 76 are screwed downward to provide space above the basin top wall to set the mirror 1 in position. The mirror is now placed between the side walls 8, 8' with its rear face substantially flush with the rear walls of the cabinets and is then rigidly clamped in position by the plates 53 and screws 54. Any space or crevice between the top wall of the basin and the bottom mirror frame member 55 is now taken up by adjustment of the sleeve members 76, and if after tightening the nuts and bolts 79 the joint is not tight, any crevice will be eliminated by further adjustment of the sleeve members. The sleeve members also serve to permit the basin to be set level on the supporting framework and provide means for overcoming differences in depth of the basin side walls, which may occur in mass production of the cast basins. When the basin and mirror have been set in final position, the panels 108 and 117 are put in place and secured by the fastening screws. The completed furniture structure is now ready for installation in a room or other compartment when the inlet and outlet piping may be connected to supply and discharge mains and the wiring electrically connected to a supply circuit at the box 124. Certain novel features of construction and arrangement disclosed in common herein and in my prior copending application Serial No. 602,413, filed April 1, 1932 and not claimed herein, are claimed in said copending application. Certain other novel features of construction and arrangement disclosed in common herein and in said application,

Serial No. 602,413, of which the present application is a continuation in part, are claimed herein.

What I claim and desire to secure by Letters Patent of the United States is:—

- 5 1. A structure of the character described, comprising laterally spaced supporting members, supporting means extending between and rigidly securing said members together, a basin positioned between said members and carried by said supporting means, and resilient means interposed between each of said supporting members and the adjacent portion of said basin.
- 10 2. A structure of the character described, comprising laterally spaced supporting members, supporting means extending between and rigidly securing said members together, a cast ceramic basin positioned between said members and carried by said supporting means, resilient means interposed between each of said members and the adjacent portion of said basin and means securing said basin to said supporting means.
- 15 3. A structure of the character described, comprising laterally spaced sheet metal cabinets, cross bars extending between and rigidly securing said cabinets together, a basin positioned between said cabinets and carried by said cross bars, and resilient means interposed between each cabinet and the adjacent portion of said basin.
- 20 4. A structure of the character described, comprising laterally spaced supporting members, a basin supported by and between said members, a mirror frame at the rear of and adapted to engage the top face of said basin, means rigidly securing said mirror frame to and supporting said mirror frame from said supporting members, and means to adjust said basin vertically for engagement of said basin with said mirror frame.
- 25 5. A structure of the character described, comprising a cabinet, a supporting member spaced laterally from said cabinet, a basin positioned between and supported by said cabinet and said member, the top wall of said basin being below the top wall of said cabinet, and means sealing the joint between said basin and said cabinet.
- 30 6. A structure of the character described, comprising a cabinet having a vertical side wall, a supporting member spaced laterally from said wall, a basin positioned between and supported by said wall and said member, a sealing strip closing the joint between the top face of said basin and said wall, means urging said strip into engagement with said wall, and means urging said strip into engagement with said basin.
- 35 7. A structure of the character described, comprising laterally spaced supporting members, supporting means fixed to and extending between said members to rigidly connect said members together, a basin having a top wall with a depending bowl and having a bottom wall, and means clamping said bottom wall to said supporting means.
- 40 8. A structure of the character described, comprising laterally spaced supporting members, supporting means fixed to and extending between said members to rigidly connect said members together, a basin having a top wall with a depending bowl and having a bottom wall, means clamping said bottom wall to said supporting means, said bowl having a waste outlet and a waste pipe connected to said outlet, and a panel extending between said members to conceal said pipe.
- 45 9. A structure of the character described, comprising a cabinet having a top wall and a side wall, a supporting member spaced laterally from said cabinet, a basin positioned between and supported by said cabinet and said member, said

basin having a top wall and a depending front apron, a bowl opening through said top wall and depending therefrom rearward of said apron, the top wall of said basin being below the top wall of said cabinet, and a sealing strip closing the space between said side wall and the adjacent edge of said apron and between said side wall and the adjacent edge of said basin top wall.

5 10. A structure of the character described, comprising a cabinet having a top wall and a side wall, a supporting member spaced laterally from said cabinet, a basin positioned between and supported by said cabinet and said member, said basin having a top wall and a depending front apron, a bowl opening through said top wall and depending therefrom rearward of said apron, the top wall of said basin being below the top wall of said cabinet, a sealing strip closing the space between said side wall and the adjacent edge of said apron and between said side wall and the adjacent edge of said basin top wall, means holding said strip in engagement with said side wall, and means holding said strip in engagement with said apron and said basin top wall.

15 11. A structure of the character described, comprising laterally spaced supporting members, a substantially horizontal framework fixed to and extending between said members to rigidly connect said members together, a basin having a top wall and a front apron depending therefrom, a bowl opening through said top wall and depending therefrom to a point below said apron, a panel extending rearward from the front of said frame and beneath said bowl and cooperating with said apron to conceal the underside of said bowl, said bowl having a waste outlet and a waste pipe connected thereto, and a panel positioned in front of said pipe and meeting said first-named panel to conceal said pipe.

20 12. A structure of the character described, comprising a cabinet having a top wall and a side wall, a supporting member spaced laterally from said side wall, a basin having a top wall and a bowl opening through said top wall, side walls depending from said basin top wall, a horizontal framework rigidly joining said cabinet and said supporting member and carrying said basin, a plate member positioned between one of said basin side walls and said cabinet side wall, a sealing strip secured to said plate member and overlying a side edge of said basin top wall, a resilient flange on said plate member engaging the bottom face of said one basin side wall and urging said strip into engagement with said basin top wall, and resilient means interposed between said plate member and said one basin side wall and urging said strip into engagement with said cabinet side wall.

25 13. A structure of the character described, comprising a cabinet having a top wall and a side wall, a supporting member spaced laterally from said side wall, a basin having a top wall and a bowl opening through said top wall, side walls depending from said basin top wall, said basin having a front apron, a horizontal framework rigidly joining said cabinet and said supporting member and carrying said basin, a plate member positioned between one of said basin side walls and said cabinet side wall, a sealing strip secured to the top and front edges of said plate member and overlying a side edge of said basin top wall and a side edge of said apron, a resilient flange on said plate member engaging the bottom face of said one basin side wall and urging said strip into engagement with said basin top wall, a resil-

ient flange on said plate member engaging the rear face of said one basin side wall and urging said strip into engagement with said apron, and resilient means interposed between said plate member and said one basin side wall and urging said strip into engagement with said cabinet side wall.

14. A structure of the character described, comprising laterally spaced supporting members, a basin member having a substantially flat top wall and a bowl depending from and opening through said wall, means securing said basin member between said supporting members, said basin member including a wall member depending from the forward edge portion of said basin member and extending between said supporting members, a closure plate extending between said supporting members and rearwardly beneath said bowl from the lower edge of said wall member, a conduit member opening into said bowl and depending therefrom, and a panel member extending between said supporting members rearward of said wall member to conceal said conduit member.

25 15. A structure of the character described, comprising laterally spaced cabinets, a basin member positioned between said cabinets and having a depending front wall extending between said cabinets, a closure member extending rearward from the lower edge of said wall and beneath said basin member, a cross-frame member extending between and secured to said cabinets adjacent their lower edges, a panel member extending between said cabinets and joining said closure member, and means securing said panel member to said cross-frame member.

16. A structure of the character described, comprising laterally spaced supporting members, supporting means fixed to and extending between said members to rigidly connect said members together, a basin mounted in said structure between the upper portions of said members and having a top wall with a depending bowl and a waste outlet connection to said bowl, said supporting means including a part extending be-

tween said members beneath the front portion of said bowl and at a level above the bottom of the bowl, and a wall concealing said outlet connection, and comprising a front portion in front of said part and a lower rearwardly extending portion beneath and adjacent the bowl and a portion depending from the rear edge of the first mentioned portion.

17. A structure of the character described, comprising laterally spaced supporting members, supporting means fixed to and extending between said members to rigidly connect said members together, a basin mounted in said structure between the upper portions of said members and having a top wall with a depending bowl and a waste outlet connection to said bowl, said supporting means including a part extending between said members beneath the front portion of the bowl at a level above the bottom of the bowl, other supporting means fixed to and extending between said members located adjacent the rear of said structure and at a lower level than said basin, and a wall concealing said outlet connection and comprising an uprising front portion in front of said part and a lower rearwardly extending portion beneath and adjacent the bowl and a portion depending from the rear edge of the first mentioned portion, and connected adjacent its lower end to said other supporting means.

18. A structure of the character described, comprising laterally spaced supporting members, supporting means fixed to and extending between said members to rigidly connect said members together, a basin mounted on said supporting means and having a top wall with a depending bowl and a waste outlet connection to said bowl, and having an apron depending from the front edge of said top wall and a wall concealing said outlet connection, and comprising a portion extending rearwardly from the lower edge of said apron beneath and adjacent the bowl and a portion depending from the rear edge of the first mentioned portion.

CECIL W. FARRAR. 45
